UNITED STATES PATENT OFFICE.

HOWARD G. MEAD, OF ST. LOUIS, MISSOURI, ASSIGNEE, BY MESNE ASSIGNMENTS, TO
WIREBOUNDS PATENTS COMPANY, OF KITTERY, MAINE, A CORPORATION OF
MAINE.

FEED MECHANISM FOR WIRE-BOUNDED BOX-BLANK MACHINES.

1,397,439.

Specification of Letters Patent. Patented Nov. 15, 1921.

Application filed July 14, 1911, Serial No. 638,575. Renewed December 20, 1919. Serial No. 346,437.

To all whom it may concern:

Be it known that I, HOWARD G. MEAD, a citizen of the United States of America, and resident of city of St. Louis, Missouri, have 5 invented a certain new and useful Improvement in Feed Mechanism for Wire-Bound Box-Blank Machines, of which the following is a specification.

My invention relates to machines for making wire bound box blanks of the kind in which reinforcing cleats are secured along the edges of the blank, and in which the different sections of the blank are flexibly or foldably connected together by a plurality of binding wires extending longitudinally thereof, the usual method being to secure the cleats to the blank by the staples which straddle the binding wires. In the manufacture of boxes of this character, it 10 has been the general practice to employ wood veneer for the side walls thereof, and under the prevailing methods of manufacture it was found preferable to use large sheets of veneer, whereby each side of the box would 15 be composed of but a single integral sheet of veneer. Lumber or stock of this character is, however, more or less expensive, as very wide sheets of veneer must be taken from selected stock. On the other hand, 20 narrow strips of veneer are often left over in the form of scrap material, and these narrow strips are, of course, cheaper and more economical to use than the large sheets. As stated, though, the character of the boxes, 25 the uses for which they are often employed, and the character of the machinery were such that only wide sheets of veneer could be used with entire satisfaction. For example, these boxes are preferably made 30 with tight corners, and for many kinds of merchandise the sides of the box must be perfectly tight and free from cracks or crevices. It was recognized that if narrow strips of veneer could be used, the cost of 35 production of these boxes would be reduced, but as no method or machinery was known for insuring a tight joint between the meeting edges of said narrow strips, in order to guard against cracks or crevices in the 40 sides of the boxes, material of this kind was not used, notwithstanding that great quantities of it would in time accumulate in the manufacture of boxes of this kind. 45 50

The object of my invention is, therefore, to provide a machine to be used in a method 55 of manufacture suitable for utilizing narrow strips of veneer in the manufacture of wire bound boxes.

With this object in view, my invention 60 contemplates the assembling of a plurality 65 of narrow strips into position to form a single side or section of the blank, with their edges held tightly together, and the wiring together of these strips of veneer while their edges are thus compressed 70 tightly together, whereby when the blank is converted into a box the side walls thereof will be perfectly tight and free from cracks or crevices, notwithstanding that each side wall will be composed of a plurality of narrow strips of veneer.

It also contemplates a feed mechanism for box blank machinery of this kind, in which provision is made for crowding the narrow strips of veneer tightly together as they pass 75 under the staplers, by causing the said strips of veneer to successively move ahead a little faster than the blank as a whole is moving, whereby any gaps or cracks between the edges of the veneer will be immediately 80 closed up or eliminated by causing the edges of the veneer to be compressed tightly together, and whereby the strips of veneer are crowded tightly together immediately before the staples are driven by which the 85 binding wires and cleats are secured in place along the edges of the blank, as will hereinafter more fully appear.

To the foregoing and other useful ends, my invention consists in matters hereinafter 90 set forth and claimed.

In the accompanying drawings—

Figure 1 is a side elevation of a wire bound box blank machine embodying the 95 principles of my invention.

Fig. 2 is a perspective of a wire bound box blank of the kind produced by the new machine embodying the principles of my invention.

Fig. 3 is a plan of the machine shown in 100 Fig. 1.

Fig. 4 is a longitudinal section of the said machine.

Figs. 5 and 6 are detail sectional views showing the manner in which one of the 105 feed wheels is adjustably secured to the

shaft to permit the manufacture of blanks of different widths.

Figs. 7 and 8 are detail views of the friction drive or pulley which has a slip connection with the shaft upon which it is mounted.

Fig. 9 is an enlarged sectional view of two edge portions of the veneer or lumber from which the sides of the blank are made, showing the two edges brought together by a tongue and groove formation.

Fig. 10 is a similar view, showing the two edges interlocked by what is ordinarily known as a ship-lap.

As thus illustrated, the said machine is of that well known and general type in which the blanks are carried under the staplers A by means of a traveling work-holder B composed of a plurality of parallel endless link belts. These link belts are carried on sprocket wheels mounted on transverse shafts b , b' , and the said endless traveling work-holder thus provided is actuated in the direction indicated by the arrow by the usual ratchet feed mechanism C which is operated by a cam c on the drive shaft D at the bottom of the machine. The cleats 1 of the blank are held in pockets in the said chains or link belts, in the usual and well known manner, and are suitably spaced apart therein, as by the well known spacing blocks. The narrow strips of veneer 2 are laid upon the tops of the cleats, in any suitable manner, and as the work passes under the staplers the cleats are secured to the veneer by the insertion of staples which straddle the binding wires 3 of the blank, these wires being fed from reels in the usual and well known manner. The machine is adjustable for blanks of different width, in the usual and well known manner, by the provision of hand wheels E and E on the shafts b and b' , whereby one of the link belts or chains can be moved toward and away from the other. The staplers are actuated in the usual and well known manner by the cross head a which is operated by the pitmen a' which are connected at their lower ends with the eccentric cams a'' , which latter are on the main drive shaft. The machine thus far is old and well known and does not require any further explanation.

It will be seen that when the machine is running with narrow strips of veneer 2, there being several strips for each section or side of the blank, there is at such time considerable danger of the said veneer being secured in place in such manner that cracks or crevices will show between the edges thereof when the blank is converted into a box. The strips of veneer can be made of substantially uniform width, and with straight and clean edges, but notwithstanding this, there is, as stated, more or less liability of the strips being secured in

place with slight space between their edges, and this would render the boxes unsatisfactory in use. In order to insure against this trouble, an auxiliary feed mechanism is provided for slightly advancing each strip of veneer before it passes under the staplers, whereby each strip of veneer is stapled in place to the cleats, and each succeeding strip of veneer is shoved up tightly against the preceding strip before it is in turn secured in place upon the cleats. This auxiliary feed mechanism comprises the transverse shaft G which extends across the machine immediately above the traveling work-holder and immediately in front of the staplers, the said shaft being mounted in suitable bracket bearings g at the ends thereof, which bearings may be suitably secured to the frame of the machine. Upon this shaft G there is mounted a pair of toothed feed wheels g' and g^2 , which feed wheels are adapted to engage the tops or upper surfaces of the strips of veneer 2, at points immediately above the cleats 1, and to thereby feed the said strips of veneer forward a little faster than they are made to move by the endless traveling work-holder. For this purpose the shaft G is preferably driven by a friction drive connection, such, for example, as a belt g^3 extending from a pulley g^4 on the shaft G, to a pulley g^5 on the shaft D, which latter pulley is shown in Figs. 7 and 8. The said pulley g^5 is mounted on the shaft D in such manner that it has a frictional connection therewith, which connection is sufficient to transmit sufficient power through the belt g^3 to the feed wheels g' and g^2 , providing there is no considerable obstruction offered to the forward movement of the veneer. With this friction drive or slip connection, however, the pulley g^5 slows down and rotates slower than the shaft D as soon as the forward edge of the strip of veneer which is directly under the feed wheels strikes the rear edge of the strip immediately ahead; and until the next or succeeding strip of veneer is encountered the said feed wheels continue to rotate and feed the veneer at the same rate of speed at which the endless traveling work-holder is moving. Then as soon as another strip of veneer is engaged by the feed wheels g' and g^2 , and if some space exists between this strip and the one immediately ahead, the adjustment of the power transmission or friction drive for this auxiliary feed mechanism is such that the feed wheels g' and g^2 move a little faster than the said rate of speed until the said space is closed up and in this way the strip of veneer is caused to jump or move suddenly ahead to an extent sufficient to bring its forward edge into firm engagement with the rear edge of the strip immediately ahead. Thus the operation of the auxiliary feed mechanism is intermit- 130

tent, so to speak, as it moves part of the time in unison with the endless traveling work-holder, and part of the time at a greater rate of speed, whereby gaps or spaces between the adjacent edges of the veneer are closed up and eliminated before the strips of veneer are secured in place upon the cleats. In this way it becomes possible to use narrow strips of veneer, such, for example, as frequently result from an accumulation of scrap material, and boxes thus made will have sides which are perfectly tight and free from cracks or crevices.

In order that the machine may be employed for making blanks of different widths, the shaft G is preferably threaded for a portion of its length, and the feed wheel g^2 is provided with a spline or feather g^6 that is movable along the groove in the said shaft. The feed wheel g^2 is provided with a hub g^9 which is rotatably connected with a nut g^8 , in any suitable manner, which nut engages the screw-threaded portion of the shaft G, whereby rotation of this nut will operate to adjust the feed wheel g^2 lengthwise of the said shaft, thus varying the distance between the two feed wheels in accordance with the widths for the blanks.

From the foregoing it will be seen that I have provided a machine which makes it possible to utilize a cheaper grade of material which was heretofore considered unsuitable for the manufacture of wire bound boxes of this kind. Each side of the box can be composed of as many strips of veneer as may be desired, and regardless of the number they will all be crowded tightly and firmly together by compression of their edges together, whereby the result and effect are practically the same as though a single sheet of veneer had been used for each side of the box.

If desired, and particularly in the manufacture of large boxes, in which the veneer or lumber is of considerable thickness, the edges of the strips can be formed with tongue and groove, or with a ship-lap, whereby when the edges are brought together they will engage tightly and in a manner that will tend to prevent one edge from warping inwardly or outwardly and away from the other. This is shown in Figs. 9 and 10, and it will be readily understood that the interlocking of the edges of the veneer can be accomplished in many other ways. In any event, though, and by employing my improved auxiliary feed mechanism, these edges will always be compressed tightly together to insure against cracks or crevices in the sides of the finished box.

The traveling work-holder B is, of course, stationary while the staples are being driven. It follows, therefore, that the feed wheels g' and g^2 are also stationary while the staples are being driven. These feed

wheels have three distinct actions as follows: First, they move at a higher rate of speed than the traveling work-holder, to cause the strip of veneer which they are engaging to move ahead and eliminate the gap or space between its forward edge and the rear edge of the strip ahead. Second, the said feed wheels then move at the same rate of speed as the traveling work-holder, whereby the strip of veneer which was shoved forward then continues moving at the same rate of speed as the traveling work-holder. Third, the said feed wheels stand still and remain motionless each time the staples are driven. Thus the entire operation of the auxiliary feed mechanism is automatic, as it adjusts itself to the conditions of the work and the mode of operation of the machine.

The feed wheels g' and g^2 can be disposed quite close to the staplers, so that the strip of veneer will be stapled to the cleats before it passes out of engagement with the said wheels. Also, if desired, a second set of similar wheels H can be positioned in front of the wheels g' and g^2 , on a shaft h like the shaft G, and connected with the latter by a sprocket chain h', whereby the desired forward pressure will always be exerted on the veneer, regardless of the width thereof, to insure the compression together of the edges thereof.

What I claim as my invention is:

1. In a machine for making wire bound box blanks, the combination of a main feed mechanism for causing the cleats and strips of veneer to move along in properly assembled relation, mechanism for stapling the veneer to the cleats, and an auxiliary feed mechanism operative to crowd the strips of veneer tightly together before they are secured to the cleats, said auxiliary feed mechanism operating at a higher rate of speed than the main feed mechanism while closing up the gap or space between any two strips of veneer, and having provisions for running at the same speed as the main feed mechanism as soon as the said gap or space is closed up or eliminated.

2. In a machine for making wire bound box blanks, the combination of an endless traveling work-holder for carrying the cleats and strips of veneer in properly assembled relation, mechanism for stapling a plurality of strips of veneer to each cleat, whereby each side or section of the blank will be composed of a plurality of strips of veneer and a plurality of cleats extending transversely thereof, and mechanism engaging said strips of veneer, to crowd them tightly together before passing under the stapling mechanism, whereby gaps or spaces are prevented from occurring between the edges of the strips of veneer of each separate side or section of the blank.

3. In a machine for making wire bound box blanks, mechanism for feeding the cleats and strips of veneer thereof at a given rate of speed, and mechanism for causing the strips of veneer to move faster at a certain point in their path of travel, to cause the edges of said strips of veneer to be brought tightly together, and mechanism for securing the strips of veneer to the cleats after the edges of the strips have been thus brought tightly together.
4. In a wire bound box blank machine, the combination of a traveling work-holder for advancing the cleats and strips of veneer in properly assembled relation, a toothed feed wheel for engaging the strips of veneer, means for operating the said feed wheel to cause the strips of veneer when thus engaged to move faster than the work-holder, whereby the edges of the veneer for each side or section of the blank are brought tightly together, and means for securing the strips of veneer to the cleats while the edges of the strips are subject to compression.
5. A machine for making box or crate blanks, comprising a main feed mechanism for the cleats and veneer, and an auxiliary feed mechanism for the veneer, arranged to operate in such a way as to cause the veneer to be crowded together on the cleats.
6. A machine for making box or crate blanks, comprising a main feed mechanism for the cleats and veneer, and an auxiliary feed mechanism for the veneer, engaging the horizontal surface thereof, said auxiliary feed mechanism being operative to feed the veneer faster at intervals than the said main feed mechanism, when the veneer is not in proper position, and being held in restraint by said main feed mechanism when the veneer is in proper position.
7. A wire bound box-blank machine comprising means for successively wiring together the several sections of the blank, and mechanism for automatically crowding together the strips of each section, before the same are wired to the cleats thereof, said mechanism being arranged to act continuously on the top of the blank.
8. A wire bound box-blank machine comprising means for successively wiring together the several sections of the blank, and mechanism for automatically shifting the sheet material on the cleats, to properly position the same, before the wiring together thereof, said mechanism being arranged to act continuously on the top of the blank.
9. A wire bound box-blank machine comprising means for successively wiring together the several sections of the blank, and mechanism for automatically crowding together the strips of each section, before the same are wired to the cleats thereof, said mechanism being arranged to act continuously on the top of the blank, together with

a traveling feed chain which governs the movement of the blanks through the machine.

10. A wire bound box-blank machine comprising means for successively wiring together the several sections of the blank, and mechanism for automatically shifting the sheet material on the cleats, to properly position the same, before the wiring together thereof, said mechanism being arranged to act continuously on the top of the blank, together with a traveling feed chain which governs the movement of the blanks through the machine.

11. A machine for making box-blanks by stapling together cleats and sheets, comprising intermittently operating means to feed the cleats and sheets in unison, at a given rate of speed, mechanism acting continuously on said sheets and tending to move a following sheet forward into edge contact with a preceding sheet, without changing the feeding motion of the cleats, and means to fasten the sheets on the cleats.

12. A machine for making box-blanks by stapling together cleats and sheets, comprising intermittently operating means to feed the cleats and sheets in unison, at a given rate of speed, mechanism acting continuously on said sheets and tending to move a following sheet forward into edge contact with a preceding sheet, without changing the feeding motion of the cleats, and means to fasten the sheets on the cleats, said mechanism being arranged to crowd the sheets edgewise together, and means to space the cleats apart between their ends.

13. A machine for making box-blanks by stapling together cleats and sheets, comprising intermittently operating means to feed the cleats and sheets in unison, at a given rate of speed, mechanism acting continuously on said sheets and tending to move a following sheet forward into edge contact with a preceding sheet, without changing the feeding motion of the cleats, and means to fasten the sheets on the cleats, said mechanism being retarded by and in step with said means while the cleats and sheets are moving in unison.

14. A box blank machine comprising means to secure together cleats and veneer sections, means for advancing said cleats and sections in assembled relation for operation of said first mentioned means thereon, feeding mechanism acting on said veneer sections, and means to drive the said feeding mechanism at a rate of speed greater than that of the advancing means, dependent in its operation on the existence of open spaces between said sections occurring between said feeding mechanism and securing means.

15. A box blank machine comprising means to secure together cleats and veneer sections, means for intermittently advancing

- said cleats and sections in assembled relation for operation of said first mentioned means thereon, feeding mechanism acting on said veneer sections, and means to drive the feeding mechanism synchronously with said advancing means and, contingently on the existence of open spaces between said sections occurring between said feeding mechanism and securing means, operating to drive said mechanism at a speed greater than that of the advancing means. 10
16. In a machine for making wirebound box blanks, the combination of a main feed mechanism for causing the cleats and sheets to move along in properly assembled relation; mechanism for securing the sheets to the cleats; and an auxiliary feed mechanism operative to advance the sheets on the cleats before they are secured to the cleats, 15 said auxiliary feed mechanism, at times, operating at a higher rate of speed than the main feed mechanism and, at other times, operating at the same speed as the main feed mechanism. 20
17. In a machine for making wirebound box blanks, the combination of a main feed mechanism for causing the cleats and sheets to move along in properly assembled relation; mechanism for securing the sheets to the cleats; and an auxiliary feed mechanism operative to deliver the sheets to said securing mechanism, said auxiliary feed mechanism, at times, operating at a higher rate of speed than the main feed mechanism and, 25 at other times, operating at the same speed as the main feed mechanism. 30
18. In a machine for making wirebound box blanks, the combination of a main feed mechanism for causing the cleats and sheets to move along in properly assembled relation; mechanism for securing the sheets to the cleats; and an auxiliary feed mechanism operative to position the sheets on the cleats, 35 said auxiliary feed mechanism, at times, operating at a higher rate of speed than the main feed mechanism and, at other times, operating at the same speed as the main feed mechanism. 40
19. In a machine for making wirebound box blanks, the combination of mechanism for feeding the cleats and sheets thereof at a given rate of speed; mechanism for causing sheets to move faster than cleats at a certain point in their path of travel, 45 to position the sheets on the cleats; and mechanism for securing the sheets to the cleats and binding wire thereto after the sheets have been so positioned. 50
20. In a machine for making wirebound box blanks, the combination of mechanism for feeding the cleats and sheets thereof at a given rate of speed; mechanism for causing sheets to move faster than cleats at a certain point in their path of travel, to 55 deliver the sheets to said first-mentioned
- feeding mechanism; and mechanism for securing the sheets to the cleats and binding wire thereto. 60
21. In a wirebound box blank machine, the combination of means for advancing the sheets and cleats in properly assembled relation; a feed wheel for engaging the sheets; means for operating said feed wheel to position the sheets on the cleats; and means for securing the sheets to the cleats. 75
22. In a wirebound box blank machine, the combination of means for advancing the sheets and cleats in properly assembled relation; a feed wheel for engaging the sheets; means for operating said feed wheel to deliver sheets to said advancing means; and means for securing the sheets to the cleats. 80
23. A machine for making wirebound box blanks comprising means to apply binding wire to box parts; a main feed mechanism for a plurality of sections of cleats and sheets; means to space said sections; and an auxiliary feed mechanism for the sheets operative to position the sheets on the cleats. 85
24. A machine for making wirebound box blanks comprising means to apply binding wire to box parts; a main feed mechanism for a plurality of sections of cleats and sheets; means to space said sections; and an auxiliary feed mechanism for the sheets operative to cause the sheets to advance on the cleats. 90
25. A machine for making box blanks comprising a main feed mechanism for the cleats and sheets; and an auxiliary feed mechanism for the sheets operative to feed the sheets, at intervals, faster than said main feed mechanism when the sheets are not in proper position, and being held in restraint by said main feed mechanism when the sheets are in proper position. 100
26. A machine for use in making wirebound box blanks comprising, in combination, means for feeding assembled cleats and sheets for a box blank; means for securing binding wire to the cleats and sheets; and mechanism for automatically shifting the sheets on the cleats to properly position the same before the wiring together thereof. 110
27. A machine for use in making wirebound box blanks comprising, in combination, means for feeding assembled cleats and sheets for a box blank; means for securing binding wire to the cleats and sheets; and means for automatically feeding the sheets faster than the cleats to properly position the same before the wiring together thereof. 115
28. In a box blank machine adapted to operate without interruption on materials for a plurality of boxes the combination of a positive feed for cleats and associated sheets; and a preliminary yielding sheet feeding means for delivering sheets to said positive feed. 125

29. A machine for use in making wire-bound cleat reinforced boxes comprising, in combination, fastener-setting mechanism for securing together cleats and sheets and applying binding wire thereto; means for positively feeding cleats and sheets and a separate and independent sheet feeding means adapted to advance the sheets on the cleats. 70
30. A machine for use in making wire-bound cleat reinforced box blanks comprising, in combination, means for wiring a succession of foldably related box sections; means for spacing said sections; means for positively feeding cleats and associated sheets; and a separate and independent sheet feeding means. 75
31. A machine for use in making wire-bound cleat reinforced box blanks comprising, in combination, means for wiring a succession of foldably related box sections; means for spacing said sections; means for positively feeding cleats and associated sheets; and preliminary sheet feeding means for automatically positioning the sheets on the cleats. 80
32. A machine for use in making wire-bound cleat reinforced box blanks comprising, in combination, means for wiring a succession of foldably related box sections; means for spacing said sections; means for positively feeding cleats and associated sheets; and sheet feeding means adapted to automatically advance the sheets on the cleats to position. 85
33. A machine for use in making wire-bound cleat reinforced box blanks comprising, in combination, means for wiring a succession of foldably related box sections; means for spacing said sections; primary means for feeding cleats and associated sheets step-by-step; and a continuously operating preliminary sheet feeding means adapted to engage the sheets, and by advancing them more rapidly than the cleats, to position them on the cleats for the wiring operation. 90
34. A machine for use in making wire-bound cleat reinforced box blanks comprising, in combination, means for wiring a succession of foldably related box sections; means for spacing said sections; means for positively feeding cleats and associated sheets; and a preliminary sheet feeding means for automatically delivering sheets to said positive feeding means, said machine being adapted to operate without interruption on materials for a plurality of boxes. 100
35. A machine for use in making wire-bound, cleat-reinforced boxes comprising, in combination, means for wiring a succession of foldably related box sections; means for spacing said sections; means for feeding cleats; and a separate and independent sheet-feeding means. 110
36. A machine for use in making wire-bound, cleat-reinforced box blanks comprising, in combination, means for wiring a succession of foldably related box sections; means for spacing said sections; means for feeding cleats; and means for advancing sheets on cleats. 120
37. A machine for use in making wire-bound, cleat-reinforced box blanks comprising, in combination, means for wiring a succession of foldably related box sections; means for spacing said sections; means for feeding cleats; and sheet-feeding means to position sheets on cleats. 125
38. In a box blank machine adapted to operate without interruption on materials for a plurality of boxes, the combination of means to apply binding wire to box parts; means for feeding cleats; and a separate and independent yielding sheet-feeding means. 130
39. A machine for use in making wire-bound boxes comprising, in combination, means for wiring a succession of foldably related sections of cleats and sheets; means to cause relative progression between said wiring means and the work; and means for pressing the sheets on the cleats to subject them in properly assembled relation to the wiring means, comprising a power driven roller adapted to engage the work. 90
40. A machine for use in making wire-bound boxes comprising, in combination, means for wiring a succession of foldably related sections of cleats and sheets; means to cause relative progression between said wiring means and the work; and means for pressing the sheets on the cleats in such a manner as to subject them in properly assembled relation to the wiring means, comprising rotatable means adapted to engage the work. 95
41. A machine for use in making wire-bound boxes comprising, in combination, means for wiring a succession of foldably related sections of cleats and sheets; means to cause relative progression between said wiring means and the work; and means for preventing the materials from buckling, and for maintaining their relative positions, comprising power driven rotatable means adapted to engage the materials. 105
42. A machine for use in making wire-bound boxes comprising, in combination, means for wiring a succession of foldably related sections of cleats and sheets; means to cause relative progression between said wiring means and the work; and means for preventing the materials from buckling and for maintaining their relative positions, comprising rotatable means bearing on the materials. 115
43. In a machine for making wire-bound box blanks, mechanism for feeding box parts at a given rate of speed; mechanism for causing box parts to move faster at a certain point in their path of travel to cause the 120
- 130

edges thereof to be brought tightly together; and mechanism for securing binding wire to box parts after the edges thereof have been thus brought tightly together.

5 44. A wire-bound box blank machine comprising means for successively wiring together the several sections of the blank, and mechanism for automatically crowding together the strips of each section before the

10 same are wired together, said mechanism being arranged to act continuously on the top of the blank.

15 45. A machine for making box blanks comprising a main feed mechanism for the box parts; and an auxiliary feed mechanism for the sheets operative to feed the sheets, at intervals, faster than the said main feed mechanism when the sheets are not in proper position, and being held in restraint by said

20 main feed mechanism when the sheets are in proper position.

25 46. A machine for use in making wire-bound boxes having a plurality of strips of side material comprising, in combination, mechanism for applying binding wire to box parts; a main feeding means for the box parts; and a preliminary feeding mechanism constructed and arranged to engage the upper surface of said strips and advance the

30 same to said main feeding means.

35 47. A machine for use in making wire-bound boxes having a plurality of strips of side material comprising, in combination, mechanism for applying binding wire to box parts; a positive feeding means for the box parts; and a frictional feeding means to deliver box material to said positive feeding means comprising a driven roller adapted to engage said strips.

40 48. A machine for use in making wire-bound boxes having a plurality of strips of side material comprising, in combination, mechanism for applying binding wire to box parts; positive feeding means for the box parts; and a preliminary feeding means to advance box material to said positive feeding means comprising a frictionally driven roller adapted to propulsively engage said strips.

45 49. A machine for use in making wire-

bound boxes having a plurality of strips of side material comprising, in combination, mechanism for applying binding wire to box parts; positive feeding means for the box parts; and frictional feeding means to crowd said strips tightly together and deliver them to said positive feeding means comprising a driven roller adapted to propulsively engage said strips.

55 50. A machine for use in making wire-bound boxes having a plurality of sheets of side material comprising, in combination, means for applying binding wire to box parts; means for positively advancing the sheets of side material; and a relatively fast friction feeder for successively forcing the sheets into desired close relation on said positive advancing means.

60 51. A machine for use in making wire-bound boxes having a plurality of sheets of side material comprising, in combination, means for applying binding wire to box parts; means for positively advancing the sheets of side material; and a relatively fast friction feeder for successively forcing the sheets into desired close relation on said positive advancing means and maintaining such relationship during the wiring operation.

65 52. A machine for use in making wire-bound boxes having a plurality of sheets of side material comprising, in combination, means for applying binding wire to box parts; means for positively advancing the sheets of side material; and a friction feeder for positioning the sheets on said positive means.

70 53. A machine for use in making wire-bound boxes having a plurality of sheets of side material comprising, in combination, means for applying binding wire to box parts; means for positively advancing the sheets of side material; and a friction feeder for positioning the sheets on said positive means for maintaining such positioning during the wiring operation.
